UNITED STATES PATENT OFFICE.

WILLIAM MOORE, OF IRONDALE, WASHINGTON.

COMBINED BEVEL AND SQUARE.

1,074,969.

Specification of Letters Patent.

Patented Oct. 7, 1913.

Application filed January 31, 1910. Serial No. 541,178.

To all whom it may concern:

Be it known that I, WILLIAM MOORE, a citizen of the United States of America, and a resident of Irondale, in the county of 5 Jefferson and State of Washington, have invented certain new and useful Improvements in Combined Bevels and Squares, of which the following is a specification.

My invention resides in the provision of 10 an improved implement embodying features of a square and a bevel combined in the form of an adjustable triangle.

The invention further resides in certain features pertaining to adjustments of the 15 implement with particular reference to ascertaining bevels, cuts and angles required in framing a hipped roof.

The invention comprises an improved construction as hereinafter set forth and 20 claimed.

In the accompanying drawings, wherein similar reference numerals designate corresponding parts throughout: Figures 1 and 2 are opposite side elevations of the 25 implement, Fig. 3 is a section on line 3—3 of Fig. 1, Fig. 4 is a section on line 4—4 of Fig. 1 and Fig. 5 is a fragmentary view of a roof framework.

In the practice of my invention I provide 30 a stock 1 preferably conforming in length to a standard spacing for rafters and comprising side pieces 2 and 3 spaced apart to receive therebetween the square 4, which is connected at the outer extremity of its 35 tongue 5 with a pivot bolt 7, seated in the side pieces 2, 3 as clearly shown.

In conjunction with stock 1 and blade 6 of the square I provide indicators, as 20 and 30 conveniently in the form of T-shaped 40 blocks which are slidably engaged in longitudinally extending slots 2', 3' of side pieces 2, 3 and constitute a washer and a nut respectively for a clamping bolt 31 which passes through a longitudinally extending slot 6' of the blade. Indicator 30 is related to graduations, as Hex. and Oct., which are provided on side piece 3 to indicate correct positions for the stock relatively to blade 6 for marking miter cuts on sticks for hexagonal and octagonal frames. Indicator 20 is related to scales R and H provided on side piece 2 for determining by angular 50 adjustments of stock 1 the length in inches and fractions thereof per foot of run, for common and hip rafters. These adjustments are based on two series of graduations

as R' and H' provided on blade 6, the first of said series bearing relation to scale R and the second to scale H. The graduations R' relate to common rafters and indicate inches of rise per foot of run and are so numbered, while the graduations H' are spaced proportionately to indicate the rise of hip rafters per foot of run and numbered consecutively for identification as to their 65 value.

In Fig. 5 I have illustrated a portion of the framework for supporting a roof, the same comprising the hip-rafters 40, common or jack-rafters 41, rafter-plate 42, purlin-plate 43, the plancher 44, and the fascia 45.

The proper use of the implement will readily be seen from the following: With the stock adjusted to any one of the 75 graduations R', as for example the graduation 8, as indicated in Fig. 1, the blade and tongue of the square will be in relative position to indicate respectively the top and bottom cuts for a common rafter having a 80 rise of 8" to one foot of run and scale R may be read, by reference to indicator 20, to ascertain the length of the rafter per foot of run. Taking the graduation of the same number in the series H' and adjusting the 85 stock thereto the length of the hip rafter per foot of run of the corresponding common rafter may be ascertained by referring to scale H.

For indicating the proper angle of the 90 stock for marking the hip rafters for tip cuts I provide on blade 6 a series of graduations T and number the same in accordance with the graduations H', and for indicating the set of the stock for marking these rafters 95 for backing a series of graduations B is provided on the tongue and numbered in a like manner to series T. Adjustments of the stock for marking miter cuts for purlin and fascia, side cuts for jack rafters and 100 face cuts for plancher are indicated by graduations M provided on the blade and numbered in the same order as the series just described, while adjustments for marking butt cuts on purlin, and down cuts on 105 purlin and plancher are indicated on the blade by respective series of correspondingly numbered graduations, as B' and D. The related graduations in the various 110 series are designated by the same numeral and the implement is therefore adjusted accordingly in framing a hipped roof after

the rise in inches per foot of run of the common rafters has been determined.

In use tongue 5 is used as a guide in marking fascia for miter cuts, jack rafters for 5 side cuts and hip rafters for cross tip cuts, while blade 6 is used as guide in marking the other cuts indicated. In all cases stock 1 is applied to the stick being framed with the tongue or blade extending over the 10 surface to be marked as will be readily understood.

The numerals accompanying the various series of graduation marks B, B', and T on Fig. 2, refer to the rise in inches per foot 15 run of the common rafters. In other words, in operating the device, for example, with a rise of eight inches per foot run of the common rafters, the side piece 3 would be adjusted throughout the several operations to 20 the numeral 8 of the various series of graduation marks.

Having thus described my invention, what I claim as new and desire to secure by Let-

ters Patent of the United States of America, is:

A device of the character described comprising a square, a stock composed of companion side pieces receiving said square therebetween, said stock being pivoted at a fixed point to said square and provided with 30 scales on one side starting from the fixed pivot point, the other blade of said square being formed with a longitudinal slot, the free end portion of said stock being formed with a longitudinal slot, blocks slidably engaged in the slots of the companion side pieces of said stock and carrying indicators associated with the graduations aforesaid, and a clamping bolt connecting said blocks and engaged in the slot of said square. 35

Signed at Seattle, Washington, this 30th day of December 1909.

WILLIAM MOORE.
